CLAIM

The ornamental design for a camcorder rain cover, as shown and described.

DESCRIPTION

FIG. 1 is a front elevational view of the camcorder rain cover showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

In FIG. 7, the broken line showing of a camcorder is for illustrative purposes only and forms no part of the claimed design. FIG. 7 is a perspective view thereof.
